UNITED STATES PATENT OFFICE.

EVAN EVANS, OF BERLIN, GERMANY, ASSIGNOR TO BERGMANN-ELEKTRICITÄTS-WERKE-
AKTIENGESELLSCHAFT, OF BERLIN, GERMANY, A CORPORATION OF GERMANY.

DEVICE FOR VENDING ELECTRICITY.

No. 914,398.

Specification of Letters Patent. Patented March 9, 1909.

Application filed January 6, 1908. Serial No. 409,413.

To all whom it may concern:

Be it known that I, EVAN EVANS, a subject of the Emperor of Germany, resident of Berlin, Germany, have invented certain new and useful Improvements in Devices for Vending Electricity, of which the following is a specification.

My invention relates to coin-controlled mechanism, particularly for vending electricity, and has for its object to provide an improved construction of such devices, especially in regard to the operation of the coin-rest.

Reference is to be had to the accompanying drawings, in which—

Figure 1 is a diagrammatic front elevation of an apparatus embodying my invention; Fig. 2 is a side elevation thereof; and Fig. 3 is a diagrammatic front elevation showing another form of circuit closer.

The coin introduced at the higher end of the inclined channel *o*, as indicated by the arrow, and rolling down on the bottom, drops through an opening at the lower end of the channel, as indicated at *t*, and thus reaches the coin-trough or coin-carrier *l*. This carrier is secured to a lever *i* pivoted at *i'* and normally held against a pin *a'* by a counterweight *i''*. The pin *a'* may be placed in any one of a series of holes *b'* so that the normal position of the lever *i* may be varied. The downward movement of the carrier, under the influence of the coin's weight, is limited by a pin *w*, adjacent to a guide channel *v* which receives the coin from the carrier *l*. The coin *t* then comes to rest temporarily upon a hook, rest or stop *u* and between two contact springs *y* and *z*, so that it closes the circuit in which the electricity sold is to be used.

The lever *i* is provided with a pawl *m* which during the downward movement of the lever operates a ratchet *n* secured to the shaft *k*, which also carries rigidly a gear wheel *p*. The latter drives two members of a planetary gearing comprising three members. One of these, *h*, meshes with the wheel *p*. The second member, *f*, is mounted to turn upon a radial stud secured to the shaft *g'* upon which the third member *e* and the first member *h* are mounted loosely. A hand *g* is secured to the shaft *g'* rigidly. The pinion *f* is in engagement with bevel teeth on the wheels *e*, *h*. The stud on which the pinion turns also carries a roll *q* which en-

gages a roll *r'* and presses it sidewise when the hand *g* points to zero, that is, when the apparatus is at rest. This roll *r'* is carried by the lever *r* pivoted at *s* and having the hook *u* at its lower end. The wheel *e* meshes with a gear *d* secured to a shaft *d'* which also carries a worm wheel *c* driven by a worm *b* on the shaft *a* of a rotary electricity meter. This meter is operated by the current in the circuit of the springs *y*, *z*, or by a current shunted therefrom. A spring *x* presses the roll *r'* toward the roll *q*.

Fig. 2 shows the mechanism at its return to the position of rest, at the moment where the coin has been released from the stop *u*. The dropping of a coin into the carrier *l* causes the latter to move downward, performing two functions: First, the wheels *n*, *p*, *h*, *f* and the shaft *g'* are rotated (while the wheel *e* remains stationary) so as to carry the roll *q* out of contact with the roll *r'* and allow the spring *x* to swing the stop *u* into the path of the coin. Second, the coin *t* is brought to the guide channel *v* and drops on to the stop *u*, closing the circuit by contact with the springs *y*, *z*. The carrier *l* is immediately returned to its normal position by the counterweight *i''*, the pawl *m* slipping over the teeth of the ratchet *n*. As soon as the circuit is closed at *y*, *z*, the meter shaft *a* begins to rotate, causing the shaft *g'* to gradually return to its normal position, through the action of the gearing *b*, *c*, *d*, *e*, *f*, *h*. Immediately before this position is reached (with the hand *g* pointing to zero) the roll *q* presses the roll *r'* aside, and thus the coin *t* is released from the stop *u*, and falls into the customary coin-receptacle; at the same time, the circuit is broken and the meter stops running. It will of course be understood that the shaft *g'* does not perform a complete revolution.

Obviously, the time during which the circuit is closed, depends on the extent of the coin carrier's movement, so that the device may be set for various lengths of time by adjusting the pin *a'*.

Instead of including the coin *t* in the circuit as in Fig. 1, I may, as shown in Fig. 3, close the circuit by the pressure of the coin on connected contact springs *y'*, *z'* normally separated from stationary contact points *y''*, *z''*. In either event, it is preferred to have the contact springs readily accessible and removable. The circuit closer shown in Fig. 1

offers the advantage of keeping the contact of the springs y, z , bright by the rubbing action of the coin; further, the circuit is closed and opened at two points, thus avoiding or reducing sparking, and, again, one of the circuit-closing elements (the coin) is always renewed.

Upon the insertion of a coin, the hand g indicates on a suitable dial the amount of 10 electricity paid for the insertion of the coin, and while the apparatus is running, the hand shows how much electricity is still to be supplied before the circuit will be broken.

One or more additional coins may be introduced while the first coin is still on the stop u . These additional coins will not operate the circuit closer, but will cause the meter to run a correspondingly greater length of time, since each downward movement of the lever i will cause electricity to be furnished during a certain period of time. When the first coin is released, the others will fall with it into the coin-receptacle. Of course, the number of coins introduced for a 25 continuous operation should never be such as to give the shaft g' a complete revolution, since this would release the coins prematurely through the action of the rolls q, r' .

I claim as my invention:

30 1. A coin-operated device, provided with a movable coin-rest for holding the coin in the position in which it causes the operation of the device, means for normally keeping said rest out of the coin's path, means, actuated by the insertion of a coin, for bringing said coin-rest into the coin's path, and means, operated by said device, for moving the coin-rest at the end of the operation to release the coin.

40 2. A coin-operated device, provided with a movable coin-rest for holding the coin in the position in which it causes the operation of the device, a movable coin-carrier arranged to convey the coin to said coin-rest, means, controlled by the movement of the coin-carrier in one direction, for moving the coin-rest into the coin's path, and means, operated by the said device, for moving the coin-rest at the end of the operation to release the coin and stop the operation.

50 3. A coin-operated device, provided with a movable coin-rest for holding the coin in the position in which it causes the operation of the device, a movable coin-carrier arranged to convey the coin to said coin-rest, actuating mechanism connected with the coin-rest, an engaging member for normally holding said mechanism in the coin-releasing position, means, controlled by the movement of the coin-carrier in one direction, for moving said engaging member a proportionate distance from the said mechanism to cause the coin rest to swing into the coin's path, and means, operated by the said device, for gradually returning said engaging

member and the coin-rest to their original positions.

4. A coin-operated device, provided with a movable coin-rest for holding the coin in the position in which it causes the operation of the device, a movable coin-carrier arranged to convey the coin to said coin-rest, actuating mechanism connected with the coin-rest, an engaging member for normally holding said mechanism in the coin-releasing position, means, controlled by the movement of the coin-carrier in one direction, for moving said engaging member away from the said mechanism, to cause the coin-rest to swing into the coin's path, and means, operated by the said device, for returning said engaging member and the coin-rest to their original positions.

5. A coin-operated device, provided with a movable coin-rest for holding the coin in the position in which it causes the running of the device, a movable coin-carrier arranged to convey the coin to said coin-rest, a planetary gearing comprising three members, a driving connection from the actuated device to one of said members, to operate it while said device is running, means, operated by the movement of the coin-carrier in one direction, for turning the second member of the planetary gearing, and thereby adjusting the third member, and means, controlled by said third member, for moving the coin-rest into the coin's path at the beginning of the operation, and for releasing the coin at the end of the operation.

6. A coin-controlled electricity vending machine, provided with a movable coin-rest for holding the coin in the position in which it effects a closing of the circuit, means for normally keeping said rest out of the coin's path, means actuated by the insertion of a coin, for bringing said coin-rest into the coin's path, and means, operated by the current, for moving the coin-rest at the end of the operation to release the coin and open the circuit.

7. A coin-controlled electricity vending machine, provided with a movable coin-rest for holding the coin in the position in which it effects a closing of the circuit, a movable coin-carrier arranged to convey the coin to said coin-rest, a planetary gearing comprising three members, driving means, operated by the current, connected with one of said members, means operated by the movement of the coin-carrier in one direction, for turning the second member of the planetary gearing, and thereby adjusting the third member, and means, controlled by said third member, for moving the coin-rest into the coin's path at the beginning of the operation and for releasing the coin at the end of the operation.

8. A coin-operated device, provided with a movable coin-rest for holding the coin in

the position in which it causes the operation of the device, a movable coin-carrier, arranged to convey the coin to said coin-rest, means for varying the throw of the coin-carrier, means controlled by the movement of the coin-carrier in one direction, for moving the coin-rest into the coin's path, and means, operated by the said device, for moving the coin-rest at the end of the oper-

ation to release the coin and stop the operation.

In testimony whereof I have hereunto set my hand, in the presence of two subscribing witnesses, this 23rd day of December 1907.

EVAN EVANS.
